UNITED STATES PATENT OFFICE.

HANS J. BEBOW, OF FOND DU LAC, WISCONSIN.

SNOWPLOW.

1,392,739.

Specification of Letters Patent.

Patented Oct. 4, 1921.

Application filed July 9, 1920. Serial No. 394,960.

To all whom it may concern:

Be it known that I, HANS J. BEBOW, a citizen of the United States, residing at Fond du Lac, in the county of Fond du Lac 5 and State of Wisconsin, have invented new and useful Improvements in Snowplows, of which the following is a specification.

The object of the invention is to provide a snow plow or snow dispensing apparatus 10 adapted for use as an attachment to a truck or automobile or other power or motor driven vehicle for facilitating the movement through snow even when the latter is drifted in such a way as to afford a serious obstacle 15 to trucks or other vehicles under normal conditions and particularly to provide a device of this type wherein the action with relation to the removal or displacement of the snow is in the paths of the wheels of 20 the vehicles to effect a clearing of the tracks through which the wheels may readily progress, and with these objects in view, the invention consists in a construction and combination of parts, of which a preferred embodiment is shown in the accompanying drawings, wherein:—

Figure 1, is a side view of a snow removing apparatus embodying the invention applied in operative position to a truck.

Fig. 2, is a plan view of the same.

Fig. 3, is a front view of the apparatus showing the relations between the complementary rotary members thereof.

Fig. 4, is a detail sectional view of one of 35 the rotary heads.

The device consists essentially of the rotary heads 10 having the spindles 11 which are disposed parallel with the path of the vehicle indicated generally at 12 and substantially in the planes of the supporting 40 wheels 13 and 14 of the said vehicle, said heads consisting of fans 15 having radially disposed blades 16 and adapted to rotate in opposite directions and with the paths of 45 the blades in intersecting relation so as to completely span the front of the vehicle covering a transverse area which is equal to or exceeds the width of the vehicle and disposed in advance of the plane of the fans 50 are the forwardly tapered augers 18 disposed in axial alignment with the fans and serving by movement in advance thereof, to loosen the snow which may have become drifted or banked in the path of the vehicle, 55 so that the lateral displacement or scattering of the same may be effectually accom-

plished by the relatively rapid rotation of the fans.

In the construction illustrated, the auger blades are provided with spindle portions 60 11^a which are detachably connected with the main spindle members 11 by means of sockets 18 carried by the former and fitted on the projecting front ends of the latter as indicated in Fig. 4, said sockets carrying set screws 19 to secure the complementary spindles in place, while the disk portions 15^a of the fans are provided with sleeves 20 fitted upon the spindles 11 and correspondingly secured by set screws 21.

The required rotary movement of the spindles may be effected by means of a special motor or by the driving motor of the vehicle as indicated at 22 in Figs. 1 and 2, a transverse shaft 23 being connected by 75 gear 24 with the rear ends of said spindles.

The fans as above indicated are adapted for rotation in opposite directions and preferably with their inner sides moving downwardly as indicated by the arrow in Fig. 3 80 to the end that the snow is thrown outwardly at the lower sides of the paths of the blade 16 to effectively open the paths for the steering and traction wheels of the vehicle.

The invention having been described, what is claimed as new and useful is:—

1. A snow removing apparatus for motor vehicles having complementary rotary fans disposed in advance of the vehicle and provided with forwardly extending augers tapering in the direction of their length to provide forward penetrating extremities, the augers being arranged in axial alignment with the fans, and means for communicating rotary motion to the fans and augers.

2. A snow removing apparatus for motor vehicles having parallel spindles disposed longitudinally with relation to the vehicle 100 and projecting in advance thereof, fan heads carried by said spindles and provided with radial blades, the blades of said fans being disposed to traverse intersecting paths, and augers arranged in advance respectively of said fan heads and carried by the fan spindles said augers being reduced toward their forward penetrating extremities.

In testimony whereof I affix my signature.

HANS J. BEBOW.
